FOOTBALL GOAL POST

Caesar Raymond Covino, 9 Rolling Hill Way,
Clark, N.J. 07066

Filed Nov. 26, 1974, Ser. No. 527,238

Term of patent 14 years

Int. Cl. D21—02

U.S. Cl. D34—5 VV

FIG. 1

FIG. 2

FIG. 1 is a front perspective view of a football goal post showing my new design; and

FIG. 2 is a front perspective view of another embodiment thereof.

I claim:

The ornamental design for a football goal post, substantially as shown and described.
